DISPLAY STRUCTURE

Daniel B. Miller, Providence, R.I., assignor to Miller Electric Co., Pawtucket, R.I., a corporation of Rhode Island

Filed Jan. 28, 1958, Ser. No. 711,602

5 Claims. (Cl. 211—1.5)

This invention relates to a structure for effectively displaying individual small articles. It is an object of the invention to provide a display structure which can be made at low cost, can be stored or shipped in knocked-down condition in a relatively small space, which is light in weight, which can quickly and easily be assembled, and which is not only eye-catching but can be made more so by causing relative movement between different sets of units or parts. For a more complete understanding of the invention reference may be had to the following description thereof, and to the drawings, of which:

Figure 1 is a somewhat schematic perspective view of structure embodying the invention;

Figure 2 is a sectional view, on a larger scale, taken on the line 2—2 of Figure 1;

Figure 3 is a perspective view of one display unit; and

Figure 4 is a plan view of a blank from which a display unit can be made.

A representative embodiment of the invention is illustrated in Figure 1. This shows a series of vertical rods 10, 12, 14 and 16 and a parallel series of vertical rods 18, 20, 22 and 24. The rods in each series are uniformly spaced apart and the rods in the front series are directly in front of corresponding rods in the rear series. To hold the rods in their vertical position, any suitable means may be employed. As shown, the rods in the front series are held at lower and near the upper ends by suitable frame members such as boards 30 and 32. In like manner the rods of the rear series are held in their relative positions by boards 34 and 36. The rods support a number of display units 40, one such unit being illustrated in Figure 3. Each unit is a hollow rectangular frustum made of a sheet material which is sufficiently rigid to hold its shape. For this purpose cardboard, sheet plastics, or sheet metal can be employed as desired. The frustum is open at its larger end and is preferably but not necessarily closed at its smaller end. Each display unit 40 may conveniently be made from a single blank such as is illustrated in Figure 4. This blank consists of a series of four trapezoidal areas 42, 44, 46 and 48 which are defined in part by crease lines 50 along their side edges. Extending from the base line of each of the areas 44 and 48 is a mirror image thereof, these images being indicated at 54 and 58, respectively. The areas 42 and 46 have mirror images 52 and 56, respectively, which are spaced therefrom by short rectangles defined by crease lines 62. The longer areas 42 and 46 have triple lines of fold 62. When the unit is folded to shape, the mirror images 54 and 58 are folded over against the areas 44 and 48, respectively. The areas 52 and 56 are folded on the three crease lines 62 to proximity with the areas 42 and 46, leaving space enough between to accommodate the vertical rods as indicated in Figures 1 and 2. The doubled walls thus formed are then folded on the lines 50 to form a hollow frustum. A flap 64 is provided on the side edge of the end area 48 to overlap a portion of the area 42 and to be attached

2

thereto adhesively or otherwise. If desired, the smaller end of the frustum can be closed by a flap 66 which is attached at one side to the smaller end of one of the areas such as 46, this flap having marginal portions 68

5 which can be tucked into the interior of the frustum and secured to the other side walls thereof adhesively or otherwise. The triple lines of fold 62 which are between the area 42 and its image 52 and between the area 46 and its image 56, result in tubular elements 70 and 72 which are shown in Figure 3 and which project slightly beyond the plane of the large open end of the frustum. These tubular elements receive and embrace rods either in the front series or the rear series as indicated in Figure 2. The rods support these display units horizontally as indicated in Figure 1. All of the units may extend in the same direction or, as illustrated, they may extend alternately in opposite directions. Figure 1 shows by way of example an array of display units arranged in columns of three and in horizontal rows of three. 10 In actual practice, there may be large numbers of units in each row and each column. Numbering the units in the columns from the bottom upward and in the horizontal rows from left to right, the rods 10 and 12 of the front series support the even numbered units in the first column, the odd numbered units in the second column, the even numbered units in the third column, and so on. The rods in the rear series support the odd numbered units in the first column, the even numbered units in the second column, the odd numbered units in the third column, and so on. 15 The rods in the rear series support the odd numbered units in the first column, the even numbered units in the second column, the odd numbered units in the third column, and so on. The tubular elements 70 and 72 on the various rods build on one another successively and thus keep the units properly spaced from one another both up and down and from side to side. It is evident that the units which are supported by the front series of rods and which point toward the rear are entirely separate and independent from the series of units which are supported by the rear rods and point toward the front. Hence to attract the eye one set of the units may be given small movement relative to the other set. These 20 movements may be back and forth, up and down or circular, the amplitude of such movements being limited by the clearance between the walls of one set of the units and the other set of the units. For this purpose a mechanism is schematically shown in Figure 1. This 25 mechanism comprises a motor 80 which drives a reduction gear unit 82. A crank wheel 84 slowly revolved by the reduction gear unit 82 oscillates a connecting link 86 which is attached to the platform or base 30 so that this base moves back and forth with respect to the base 34 which adjoins it. With this mechanism, the display units which are supported by the front series of rods 30 are moved relatively with respect to the other display units which are supported by the rear series of rods. 35 Striking displays can be had by the judicious use of bright colors on the outside walls of the individual units and on the ends 66 thereof. The interior of each unit is preferably but not necessarily white so as to set off to the best advantage articles which are to be displayed. Such articles may conveniently be suspended from an 40 aperture in the top wall of each unit. For this purpose a suitable hole or aperture 90 (in Figures 3 and 4) is provided in the inner layer of the top wall of each unit as it is supported by the vertical rods. This hole can be of any convenient size or shape and is preferably 45 adapted to facilitate the suspension of a small article by a button which can be inserted through the hole 90 and moved to a narrow end portion of this hole. 50 The display structure hereinbefore described is relatively light in weight and can easily be assembled and 55 disassembled. When disassembled, the parts can be readily nested to save space or, if the individual units have 60 been put together by detachable fasteners, the units can 65 be readily separated. 70

be unfolded to flat form as shown in Figure 4, and packed one upon another.

It is evident that various modifications and changes may be made in the embodiment of the invention herein shown and described without departing from the scope thereof as defined in the following claims.

I claim:

1. A display structure comprising a series of vertical rods disposed in a common plane, means holding said rods in position, and hollow frusto-pyramidal units mounted on said rods with their axes horizontal and their larger ends open between successive rods to receive articles for display, each said unit having a tubular rim along the entire length of each of two opposed edges of its larger end to receive said rods, the units between any two of said rods being vertically over one another and spaced by the tubular rims of the laterally adjacent units supported by said two rods and the rods next adjacent thereto, whereby the units are arranged in checkerboard array with intervening spaces between adjacent display units.

2. A display structure comprising two parallel series of uniformly spaced vertical rods, means holding said rods in position, and a series of display units consisting of hollow rectangular pyramidal frustums open at the larger end to receive articles for display and supported at said larger ends by each of said series of rods with their axes horizontal in vertical columns and horizontal rows between said two series of rods, each said series of rods supporting every other display unit in every row and column of the structure, the other series of rods supporting the remainder of the units in the structure, said series of display units being nested each with the other.

3. A display structure as in claim 2, each said display unit having tubular elements along two of the sides of its open end embracing two rods in one of said series as the sole support of said unit.
5. A display structure as in claim 3, each said display unit consisting of sheet material cut and folded so that each side wall of each said frustum is double, the folds at two of said side walls forming said tubular elements.
5. A display structure comprising a number of display units arranged in horizontal rows and vertical columns, each unit consisting of a horizontally disposed hollow rectangular pyramidal frustum, open at the larger end to receive articles for display and closed at the smaller end, supporting means for said units comprising two parallel series of vertical spaced rods, every other unit in each row and column being attached at their larger end to rods of one said series and supported thereby, the remainder of the units being similarly attached to and supported by rods of the other said series, relatively movable means separately supporting each of said series of rods, and means for causing small relative movements between the two supporting means and series of rods and units attached thereto.
